UNITED STATES PATENT OFFICE

EDWARD V. OEHLER, OF MILWAUKEE, WISCONSIN, ASSIGNOR TO PHOENIX HOSIERY COMPANY, OF MILWAUKEE, WISCONSIN, A CORPORATION OF WISCONSIN

PACKING HOSIERY

Application filed April 18, 1929. Serial No. 356,059.

This invention relates to an improved package particularly designed and adapted for use with hosiery.

It is customary for hosiery manufacturers 5 to ship hosiery from the factory to the retailer in small boxes, each of which contains a number of pairs of hosiery. Modern retail merchandising requires the tagging or marking of all merchandise. This is usually 10 accomplished by pinning tickets or tags on each article of merchandise and printing on the ticket so attached, information, which may be in code, and which concerns type, size, price, color, and a season symbol or invoice number. When the boxes of hosiery 15 are received by the retail merchant from the manufacturer they are taken to the marking room and opened. If any wrapping is employed for the hosiery within the box this 20 must be removed and the hosiery must be unfolded and each pair of hose handled separately in order to present each pair of hose to the machine usually employed to pin or otherwise secure the marking tags or tickets 25 to the hosiery and to print the desired information on the tickets. This handling of the hosiery is extremely undesirable for a number of reasons, and first of all, because of the damage that is done thereto. Many of 30 the modern types of hosiery are rather delicately constituted and if caught on any rough or sharp surface or object or even if abraded will be seriously injured. In fact, from two to three per cent of all of the present popular 35 light weight chiffon hosiery now manufactured is damaged or injured in some way due to the handling incidental to marking or tagging. Another serious objection is the fact that even when the hosiery is not damaged 40 its appearance is somewhat disturbed or impaired. Articles of this kind must have a fresh and attractive appearance in order to have the essential sales appeal over the counter of the retail merchant and the freshness and attractive appearance of hosiery 45 suffers from the handling heretofore incident to the marking process.

One of the principal objects of the present invention is to provide a package for the 50 hosiery contained in the ordinary box which

will permit of tagging or marking of the several pairs of hose without necessitating removal of the wrappers or envelopes from the hosiery or the unfolding of the hosiery so that the hosiery is protected and its appearance is preserved during the marking or tagging. And because it is not necessary to unfold the hosiery or to remove the wrapping or package therefrom during the marking, the marking operation itself is facilitated. 55 But the principal advantage resides in the protection of the hosiery and the preservation of the freshness and attractiveness of its appearance thereby preventing damage to the hosiery. Along with these advantages 60 the present invention provides a package which will prevent sliding of the hosiery during shipment. During shipment the forces acting on the hosiery tend to cause it to slide in the box in which it is contained and consequently 65 to bunch and wrinkle. This is precluded by the package embodying applicant's invention and this result is had while minimizing handling of the hosiery during marking and consequently protecting the hosiery 70 and preserving its appearance. 75

Other objects and advantages reside in certain novel features of the construction, arrangement and combination of parts which will be hereinafter more fully described and 80 particularly pointed out in the appended claims, reference being had to the accompanying drawings forming a part of this specification and in which:

Figure 1 is a perspective view showing a 85 package embodying the present invention and placed in the lower half of the ordinary box, the top of the box being omitted as it is conventional and well known;

Figure 2 is a similar view showing how 90 each pair of hosiery and its wrapping or envelope may be folded forwardly to expose the underlying pair and its wrapping; and

Figure 3 is a perspective view of one of the individual envelopes or wrappers provided 95 for each pair of hosiery.

Referring to the drawings, numeral 1 designates the lower half of a conventional box in which hosiery is usually shipped. Such boxes are ordinarily equipped with a cover 100

similar to the bottom although slightly larger and into which the bottom telescopes. This cover is not shown as it is conventional and widely known and used. Into such a box a number of pairs of hosiery are placed. For instance, it is quite usual to ship three pairs of hosiery in a box although, of course, the number may be varied. The hosiery of each pair is folded in any suitable way, but with applicant's invention the lower portion of the hose is folded up onto the upper portion, a portion of the foot is then folded over within the confines of the upper portion and the lower folded portion is then again folded up onto the foot portion. The exact method of folding is not so important so long as an upper corner of the upper end or top of the hose is left exposed as with applicant's invention the tags or marking tickets T are applied to this exposed corner of the upper end of the hosiery.

An individual envelope or wrapper 2 is provided for each pair of hose and is folded upon itself to provide a lower wall 3 and an upper wall 4 between which the hosiery is received. The wall 3 has an extension 3^a which extends over the top of the hosiery and beneath the upper wall 4 thereby confining and enclosing practically all of the surface of the hosiery. The walls 3 and 4 are cut away at an angle as indicated at 3' and 4' to expose the upper corner or rather one of the upper corners of the top or upper end of the hosiery. The pairs of hosiery and individual wrapping as thus described are placed one on top of the other and are held together by means of an endless band 5 which slightly compresses the wrappers and the hosiery and utilizes the elasticity of the hosiery to hold it in position and to hold the wrappers against displacement relative to each other and the hosiery against displacement relative to the wrappers. The band 5 may consist of a strip of paper having its ends overlapping and pasted together.

With the hosiery so packaged in the ordinary box it will not slide and consequently bunch or wrinkle, because the wrappers or envelopes conform to the size and shape of the box and engage the walls thereof. And when the box of hosiery is received by the retailer and is sent to the marking room for the application of the marking tickets or tags it is not necessary to remove the band 5 or the wrappers or envelopes 2. All of the hosiery in the box is taken out together and while left in its original condition and original packaging. The operator may hold the entire package with one hand and by lifting up the exposed corner of the upper pair may insert in the marking machine and apply the marking tag T thereto and print the appropriate information on the tag. After the marking tag has been applied to the uppermost pair, the uppermost pair of ho-

siery and its wrapping is flexed or bent backwardly to expose the next pair which is similarly marked and then bent backwardly to expose the lowermost pair. As the hosiery is not unwrapped and is not unfolded, it will not be wrinkled nor will it have its fresh or attractive appearance otherwise impaired by the marking. Of equal importance is the fact that the hosiery is enclosed and protected during the marking operation, especially as to its delicate portions.

What I claim is:

A package for hosiery including an individual wrapping for each pair of hosiery, a plurality of said individual wrapping with their pairs of hosiery folded therein being placed one upon another and a band encircling all of said wrappers for holding the same together and against displacement, a portion of each wrapping being removed to expose a portion of the hosiery contained therein whereby marking tickets may be applied to each pair of hosiery while the hosiery is folded and enclosed in its wrapping and while the wrappers are held together by the band.

In witness whereof, I hereto affix my signature.

EDWARD V. OEHLER.
